(57) **CLAIM**

The ornamental design for a vehicle grille, as shown and described.

DESCRIPTION

FIG. 1 is a front view of a vehicle grille according to the present invention, with the grille shown within the broken line.

FIG. 2 is an enlarged front view of the grille shown in FIG. 1.

FIG. 3 is a front left perspective of the grille shown in FIG. 1; and,

FIG. 4 is an enlarged front left perspective view of the grille shown in FIG. 3.

In FIGS. 1-4, the broken line forms an unclaimed boundary, and any elements shown outside thereof form no part of the claimed design, but are instead included to show environmental aspects thereof. Also, in FIGS. 2 and 4 the de-emphasized and halftone portions located outside the broken line form no part of the claimed design, but are instead included to illustrate environmental structure.
